(57) **ABSTRACT**

A secure beverage container includes a body having a first end, and a second end opposing the first end. The secure beverage container includes a lid assembly to be received by the second end. The lid assembly includes a lid housing, a sipper carried by the lid housing, a latch carried by the lid housing and configured to selectively latch to adjacent portions of the body, and a mechanical assembly carried by the lid housing and coupled to the sipper and the latch. The mechanical assembly is configured to operate in one of a locked state, and an unlocked state. The lid assembly also includes an access control device carried by the lid housing and coupled to the mechanical assembly, the access control device configured to cause the mechanical assembly to switch between the locked state and the unlocked state based upon a security token.

SECURE BEVERAGE CONTAINER WITH LOCKING FEATURE AND RELATED METHODS

RELATED APPLICATIONS

This application is a continuation-in-part of U.S. application Ser. No. 17/664,264 filed May 20, 2022, which is a continuation of U.S. application Ser. No. 17/304,870 filed Jun. 28, 2021, now U.S. Pat. No. 11,345,528, which is a continuation of U.S. application Ser. No. 17/136,223 filed Dec. 29, 2020, now U.S. Pat. No. 11,077,997, which is a continuation of Ser. No. 16/191,593 filed Nov. 15, 2018, now U.S. Pat. No. 10,894,643, which are hereby incorporated herein in their entireties by reference.

TECHNICAL FIELD

The present disclosure relates to the field of beverage accessories, and, more particularly, to a beverage container and related methods.

BACKGROUND

In many social events and gatherings, it is custom to consume food and beverages. Indeed, in American culture, it is quite common to consume alcoholic beverages in a wide range of events, such as happy hours, business events, and social events. Given that some events are highly attended, it is not uncommon for beverages to be dispensed in identical disposable containers, such as the ubiquitous plastic beverage container.

In these scenarios, the security of your beverage container is generally not a concern. This lack of security can create serious consequences for patrons of these events. Beyond the typical cross-contamination issue between patrons inadvertently exchanging beverage containers, there are also risks due to more nefarious actors.

Most prominently, some bad actors may intentionally attempt to adulterate a patron's beverage container to commit a drug-facilitated sexual assault (DFSA), more commonly known as a date rape. Indeed, it is not uncommon for date rape crimes to start with the adulteration of the beverage container with a hallucinogenic or incapacitating substance, such as rohypnol, ketamine, zopiclone, methaqualone, zolpidem (Ambien), sedatives, ethanol, cocaine, barbiturates, opioids, phenacyclidine, and scopolamine. Indeed, some statistics suggest that 1 in 5 women in the United States is a victim of date rape.

Given the danger of DFSA from unknown bad actors, there have been some approaches to protecting a patron's beverage container at these large scale events. In one approach, a smart coaster monitors the status of a beverage container placed thereon. In another approach, for example, U.S. Patent Application Publication No. 2017/0160253 discloses a beverage container that can detect when the beverage therein has been contaminated.

SUMMARY

Generally, a secure beverage container comprises a body comprising a first end, a second end opposing the first end, a first longitudinal side extending between the first end and the second end, and a second longitudinal side opposing the first longitudinal side and extending between the first end and the second end. The first end is closed, and the second end is open. The body defines a cavity therein to receive a

beverage fluid. The secure beverage container also includes a lid assembly to be received by the second end to seal the cavity in the body. The lid assembly comprises a lid housing, a sipper carried by the lid housing and providing access to the cavity, a latch carried by the lid housing and configured to selectively latch to adjacent portions of the body, and a mechanical assembly carried by the lid housing and coupled to the sipper and the latch. The mechanical assembly is configured to operate in one of a locked state where the latch is latched to the adjacent portions of the body, thereby securing to the second end of the body, and an unlocked state when the lid assembly can be removed from the second end of the body. The lid assembly also includes an access control device carried by the lid housing and coupled to the mechanical assembly, the access control device configured to cause the mechanical assembly to switch between the locked state and the unlocked state based upon a security token.

In particular, the mechanical assembly may comprise a motorized device, a linkage coupled between the sipper and the motorized device, and a bias device coupled to the linkage and configured to bias the mechanical assembly to be in the locked state. The latch may comprise a pinlock body coupled to the linkage, and a pin coupled to the pinlock body and configured to extend into the adjacent portions of the body in the locked state and retract from the adjacent portions of the body in the unlocked state. The sipper may comprise a sipper housing defining a fluid passageway therethrough, and first and second arms extending from the sipper housing and to be received by the linkage. The linkage may comprise first and second linkage arms configured to receive the first and second arms of the sipper, and a medial arm between and extending opposite to the first and second linkage arms and to cooperate with the motorized device. Each of the first and second linkage arms may comprise a transverse pin cooperating with the pinlock body.

Also, the motorized device may comprise an electric motor coupled to the access control device, and a cam coupled to the electric motor and to abut and push the linkage into the unlocked state. The motorized device may comprise a waterproof diaphragm covering the cam. The access control device may comprise a wireless access control device configured to receive the security token wirelessly from a wireless communications device.

Another aspect is directed to a method for making a secure beverage container. The method includes forming a body comprising a first end, a second end opposing the first end, a first longitudinal side extending between the first end and the second end, and a second longitudinal side opposing the first longitudinal side and extending between the first end and the second end. The first end is closed, and the second end is open. The body defines a cavity therein to receive a beverage fluid. The method also includes positioning a lid assembly to be received by the second end to seal the cavity in the body and comprising a lid housing, a sipper carried by the lid housing and providing access to the cavity, a latch carried by the lid housing and configured to selectively latch to adjacent portions of the body, and a mechanical assembly carried by the lid housing and coupled to the sipper and the latch. The mechanical assembly is configured to operate in one of a locked state where the latch is latched to the adjacent portions of the body, thereby securing to the second end of the body, and an unlocked state when the lid assembly can be removed from the second end of the body. The lid assembly also includes an access control device carried by the lid housing and coupled to the mechanical assembly, the access control device configured to cause the mechanical

assembly to switch between the locked state and the unlocked state based upon a security token.

BRIEF DESCRIPTION OF THE DRAWINGS

FIG. 1 is a schematic diagram of a first embodiment of the secure beverage container, according to the present disclosure.

FIG. 2 is a schematic diagram of a second embodiment of the secure beverage container, according to the present disclosure.

FIG. 3 is a schematic diagram of a third embodiment of the secure beverage container, according to the present disclosure.

FIG. 4 is a schematic diagram of a fourth embodiment of the secure beverage container, according to the present disclosure.

FIG. 5 is a schematic diagram of a fifth embodiment of the secure beverage container, according to the present disclosure.

FIG. 6 is a flowchart for a method of operating the embodiments of the secure beverage container from FIGS. 1-5.

FIG. 7 is a perspective view of a sixth embodiment of the secure beverage container, according to the present disclosure.

FIG. 8 is another perspective view of the secure beverage container from FIG. 7 with the lid assembly removed.

FIGS. 9A-9E are cross-sectional views of the secure beverage container from FIG. 7 along line 9-9.

FIG. 9F is a cross-sectional view of the secure beverage container from FIG. 7 along line 9F-9F.

FIGS. 10A-10B are perspective views of the lid assembly of the secure beverage container from FIG. 7 with an upper housing removed.

FIGS. 11A-11B are perspective views of the mechanical assembly of the secure beverage container from FIG. 7.

FIG. 12 is a perspective view of the pinlock body and the linkage from the secure beverage container from FIG. 7.

FIG. 13 is a flowchart for a method of operating the secure beverage container from FIG. 7.

DETAILED DESCRIPTION

The present disclosure will now be described more fully hereinafter with reference to the accompanying drawings, in which several embodiments of the invention are shown. This present disclosure may, however, be embodied in many different forms and should not be construed as limited to the embodiments set forth herein. Rather, these embodiments are provided so that this disclosure will be thorough and complete, and will fully convey the scope of the present disclosure to those skilled in the art. Like numbers refer to like elements throughout, and base 100 reference numerals are used to indicate similar elements in alternative embodiments.

Referring initially to FIG. 1, a secure beverage container 10 according to the present disclosure are now described. The secure beverage container 10 illustratively includes a body 11. The body 11 illustratively comprises a substantially cylinder-shape. Of course, this shape is merely exemplary, and the body 11 may have other shapes, such as a truncated-cone shape, a truncated-pyramid, or a polygonal frustum, for example.

The body 11 illustratively includes a first end 12, a second end 13 opposing the first end, a first longitudinal side 14 extending between the first end and the second end, and a

second longitudinal side 15 opposing the first longitudinal side and extending between the first end and the second end. In the illustrated embodiment, the first longitudinal side 14 and the second longitudinal side 15 are substantially parallel (i.e. parallel $\pm 5^\circ$), but they may be canted in other embodiments. The first end 12 is closed, and the second end 13 is open.

The body 11 defines a cavity 16 therein to receive a beverage fluid. In some embodiments, the body 11 comprises insulating material to reduce thermal exchange between ambient air and the beverage fluid. The secure beverage container 10 illustratively includes a lid 17 to be received by the second end 13 to seal the cavity 16 in the body 11. The body 11 may comprise one or more of a polymer plastic material, a ceramic material, or a metallic material.

The secure beverage container 10 illustratively includes a powered locking device 18 configured to operate in one of a locked state (locked cycle) where the lid 17 is secured to the second end 13 of the body 11 (i.e. the lid cannot be removed forcibly), and an unlocked state (unlocked cycle) when the lid can be readily or easily removed from the second end of the body. In some embodiments, the powered locking device 18 may comprise a servomotor. In other embodiments, the powered locking device 18 may comprise a mechanical user driven locking mechanism, such as a key-turned lock. In this embodiment, the access control device 20 is configured to permit activation of the mechanical user driven locking mechanism based upon presence in the locked state and unlocked state. Helpfully, in the locked state, the beverage fluid in the cavity 16 cannot be accessed nor can it be adulterated unbeknownst to the user.

The secure beverage container 10 illustratively includes an access control device 20 coupled to the powered locking device 18 and configured to cause the powered locking device to switch between the locked state and the unlocked state based upon a security token. The access control device 20 comprises a controller (e.g. a processor, processing circuitry,) configured to control a state of the powered locking device 18.

In the illustrated embodiment, the access control device 20 comprises a biometric scanner device, and the security token comprises a biometric characteristic of a user, for example, a fingerprint characteristic or a voice biometric characteristic. In some embodiments, the access control device 20 may comprise a voice command interface configured to permit switching between the locked and unlocked states using voice prompts (e.g. "lock" or "close", and "unlock" or "open"). In other embodiments, the access control device 20 comprises an alphanumeric keypad, and the security token comprises an alphanumeric key string. In yet other embodiments, the access control device 20 comprises a keyed or combination mechanical lock, and the security token comprises a physical key or a combination key.

In the illustrated embodiment, the powered locking device 18 is carried by the lid 17 and comprises a latch mechanism 21a-21b configured to selectively latch to adjacent portions of the body 11. In particular, the latch mechanism 21a-21b extends laterally outward into respective recesses 26a-26b in an interior wall of the body 11. Moreover, the secure beverage container 10 illustratively includes a battery power source 22 carried by the lid 17 and being coupled to the powered locking device 18 and the access control device 20. In short, in this embodiment, the smart logic and power devices are all carried by the lid 17. Some embodiments of

the secure beverage container 10 include physical security features for the battery power source 22 to prevent circumvention attempts.

The secure beverage container 10 illustratively includes a visual indicator 23 (e.g. a light emitting diode (LED) indicator) coupled to the access control device 20 and configured to generate a visual indication (e.g. steady light, or rapid flashing) when the powered locking device 18 is in the unlocked state and/or when the powered locking device 18 is in the unlocked state for a time period greater than a set time period (e.g. 25 seconds). In embodiments where the secure beverage container 10 is coupled to a mobile wireless device of the user, the visual indication can be transmitted to the mobile wireless device as a mobile OS system notification. In some embodiments, the secure beverage container 10 includes a visual indicator 23 configured to generate a low battery indication.

In some embodiments, the visual indicator 23 can be omitted, or replaced with vibration indicators. Indeed, in some embodiments, the secure beverage container 10 illustratively includes a proximity detector (not shown) carried by the lid 17 and configured to detect when the lid is placed within the second end 13 of the body 11. In these embodiments, when the lid 17 is in position, the powered locking device 18 would automatically enter the locked state.

Referring now additionally to FIG. 6, a method for operating the secure beverage container 10, with reference to a flowchart 50, according to the present disclosure is now described. (Block 51). The powered locking device 18 only exits the locked state when the security token is received. (Blocks 53, 55, 59, 63). Also, while in the unlocked state, the powered locking device 18 is configured to enter the locked state when the lock command is received. (Blocks 57, 61, 63).

In typical use, the user would need to place the powered locking device 18 in the unlocked state to add more beverage fluid or to drink the beverage fluid. In the illustrated embodiment, the lid 17 may comprise a sipping opening 30 permitting the beverage fluid to flow outward, and not inward. For example, the sipping opening may include a check valve coupled thereto, and the check valve may be controlled by the access control device 20. Advantageously, this permits easy access to the beverage fluid for consumption yet still blocks potential adulteration.

Another aspect is directed to a method for making a secure beverage container 10. The method includes forming a body 11. The body 11 includes a first end 12, a second end 13 opposing the first end, a first longitudinal side 14 extending between the first end and the second end, and a second longitudinal side 15 opposing the first longitudinal side and extending between the first end and the second end. The first end 12 is closed, and the second end 13 is open. The body 11 defines a cavity 16 therein to receive a beverage fluid. The method comprises forming a lid 17 to be received by the second end 13 to seal the cavity in the body, and coupling a powered locking device 18 configured to operate in one of a locked state where the lid is secured to the second end of the body, and an unlocked state when the lid can be removed from the second end of the body. The method also comprises coupling an access control device 20 to the powered locking device 18 and configured to cause the powered locking device to switch between the locked state and the unlocked state based upon a security token.

Referring now additionally to FIG. 2, another embodiment of the secure beverage container 110 is now described. In this embodiment of the secure beverage container 110, those elements already discussed above with respect to

FIGS. 1 and 6 are incremented by 100 and most require no further discussion herein. This embodiment differs from the previous embodiment in that this secure beverage container 110 illustratively includes the powered locking device 118 carried by the body 111. Also, in this embodiment, the access control device 120, the battery 122, the visual indicator 123 are all carried by the body 111 rather than the lid, as in the first embodiment.

In this embodiment, the access control device 120 comprises a pressure mechanism configured to lower pressure within the cavity 116 of the body 111 when in the locked state. In particular, the pressure mechanism illustratively includes an air pressure source 124 configured to exhaust air from the cavity 116 when in the locked state to create negative pressure in the cavity. The exhaust process would conclude when an internal cavity pressure hits a minimum threshold pressure differential great enough to lock the lid 117 to the body 111.

The pressure mechanism illustratively includes a valve device 125 (e.g. a 1-way valve, or check valve) configured to permit airflow into the negative pressure in the cavity 116 when switching from the locked state to the unlocked state. In other words, in the locked state, the access control device 120 creates an internal pressure within the cavity 116 that is lower than an ambient atmospheric pressure, thereby creating a partial vacuum in the cavity 116 and making removal of the lid 117 very difficult. As will be appreciated, the pressure mechanism includes a second valve (not shown) and coupled between the air pressure source 124 and the cavity 116. This second valve is closed during typical operation and opens only when creating the negative pressure in the cavity 116. In some embodiments, the second valve and the valve device 125 may be integrated as a single valve device. In the illustrated embodiment, the battery 122 is carried at the first end 112 of the body 111, but in other embodiments, the battery can be carried on the first and second longitudinal sides 114, 115.

Referring now additionally to FIG. 3, another embodiment of the secure beverage container 210 is now described. In this embodiment of the secure beverage container 210, those elements already discussed above with respect to FIGS. 1 and 6 are incremented by 200 and most require no further discussion herein. This embodiment differs from the previous embodiment in that this secure beverage container 210 illustratively includes the powered locking device being carried by the body 211 and comprising an electromagnet mechanism 218a, 218b configured to secure the lid 217 to the body. In the illustrated embodiment, the electromagnet mechanism 218a, 218b is carried by an interior wall of the body 211.

Also, the lid 217 comprises a ferromagnetic material, for example, iron, cobalt, or nickel. In some embodiments, the lid 217 may comprise a plastic or non-ferromagnetic housing carrying a ferromagnetic body therein. In other embodiments, the lid 217 may entirely comprise the ferromagnetic material. So, in the locked state, the electromagnet mechanism 218a, 218b is energized, thereby magnetically coupling the lid 217 to the second end 213 of the body 211. In the unlocked state, the electromagnet mechanism 218a, 218b is unpowered.

In one embodiment, the electromagnet mechanism 218a, 218b comprises a permanent electromagnet, i.e. an electromagnet having a permanent magnetic field, and when supplied with power, the magnetic field being turned off or more specifically neutralized. In this embodiment, in the unlocked state, the electromagnet mechanism 218a, 218b is energized to neutralize the permanent magnetic field.

Referring now additionally to FIG. 4, another embodiment of the secure beverage container 310 is now described. In this embodiment of the secure beverage container 310, those elements already discussed above with respect to FIGS. 1 and 6 are incremented by 300 and most require no further discussion herein. This embodiment differs from the previous embodiment in that this secure beverage container 310 illustratively includes a powered locking device 318a-318b carried by the body 311, in particular, an interior wall of the body.

The powered locking device 318 illustratively includes a latch mechanism 321a-321b configured to selectively latch to adjacent portions of the lid 317 via a vertical path of travel. In particular, the lid 317 would include respective recesses 326a-326b for receiving the latch mechanism 321a-321b. In the illustrated embodiment, the lid 317 comprises an annular threaded surface, and the body 311 defines an internal threaded surface for threadingly engaging the lid. Hence, when the latch mechanism 321a-321b extends the latches vertically, the twisting motion of the lid 317 is prevented, and the lid is secured to the body 311. In some embodiments (e.g. embodiments where the lid 317 is friction coupled to the body 311), the latch mechanism 321a-321b comprises curved latches for retaining the lid 317 securely in the locked state.

Referring now additionally to FIG. 5, another embodiment of the secure beverage container 410 is now described. In this embodiment of the secure beverage container 410, those elements already discussed above with respect to FIGS. 1 and 6 are incremented by 400 and most require no further discussion herein. This embodiment differs from the previous embodiment in that this secure beverage container 410 illustratively includes a wireless access control device 420 comprising a wireless receiver/transceiver. For example, the wireless receiver/transceiver may comprise a near field communications (NFC) receiver/transceiver, or a Bluetooth receiver/transceiver.

The wireless receiver/transceiver is configured to receive a key from an associated mobile wireless communications device 427 of the user (e.g. a mobile cellular device, a smart watch, a tablet computing device, or a passive NFC identification tag, such as a key fob NFC tag, or an human body embedded NFC tag, as available from Biohax International of Stockholm, Sweden). The mobile wireless communications device 427 includes a processor 428 and memory 429 cooperating therewith to transmit the security token to the wireless access control device 420. In these wireless embodiments, the wireless receiver/transceiver can use a signal strength measurement as a proxy measurement for detecting a proximity of the user. Indeed, the access control device 420 may cause the powered locking device 418 to automatically enter the unlocked state when the user is detected within a threshold proximity, and automatically cause the powered locking device to enter the locked state when the user exceeds the threshold proximity, for example, when the user leaves the secure beverage container 410 unattended.

In yet other embodiments, the associated mobile wireless device of the user may control the state of the powered locking device 410. In particular, the powered locking device 418 locked/unlocked state may follow the lock state of the mobile operating system (OS) of the mobile wireless device. In other words, when the mobile wireless device is unlocked via, a biometric characteristic, for example, the powered locking device 418 is also unlocked, and when the mobile wireless device is locked, the powered locking device 418 is also locked.

As will be appreciated, in some embodiments, the powered components are carried by the lid (See FIGS. 1 & 5), and in other embodiments, the powered components are carried by the body (See FIGS. 2-4). It should be appreciated that these powered components can be carried alternatively by either the body or the lid, or even a selective combination therebetween. Also, it should be appreciated that the features of the embodiments can be applied equally to all of the other embodiments.

10 Indeed, in some embodiments that apply the air pressure approach of FIG. 2, the powered components can all be carried by the lid. Moreover, the lid may also comprise a sealing member extending about a periphery of a lower surface of the lid, which mates with the second end of the body.

15 The sealing member may comprise a rubber gasket or a neoprene seal, for example. The sealing member would create an air tight seal with anybody sharing a common size with the lid, permitting the lid to be mated with a wide 20 variety of beverage containers. The bottom of the lid may consist of an injection molded rubber or neoprene shell and the entire bottom will be the sealing member of the lid. The specific durometer of the rubber or neoprene will allow the top portion of the body to recess into the rubber or neoprene.

25 Referring now to FIGS. 7-12, another embodiment of the secure beverage container 510 is now described. The secure beverage container 510 illustratively includes a body 511 comprising a first end 512, a second end 513 opposing the first end, a first longitudinal side extending between the first 30 end and the second end, and a second longitudinal side opposing the first longitudinal side and extending between the first end and the second end. The first end 512 is closed, and the second end 513 is open. The body 511 defines a cavity 514 therein to receive a beverage fluid. The secure 35 beverage container 510 also includes a lid assembly 515 to be received by the second end 513 to seal the cavity 514 in the body 511.

The lid assembly 515 illustratively includes a lid housing 516 comprising a lower housing 517, an upper housing 520 40 coupled to the lower housing via an adhesive layer or fasteners, for example, and an O-ring 545 carried by the lower housing and configured to provide a waterproof seal for the cavity 514. The lid housing 516 may comprise any 45 rigid material of sufficient mechanical strength, for example, a polymer plastic, a metallic material, or a combination thereof.

The lid assembly 515 illustratively includes a sipper 521 50 carried by the lid housing 516 and providing access to the cavity 514, a latch 522 carried by the lid housing and configured to selectively latch to adjacent portions of the body 511, and a mechanical assembly 523 carried by the lid housing and coupled to the sipper and the latch. The 55 mechanical assembly 523 is configured to operate in one of a locked state where the latch 522 is latched to the adjacent portions of the body 511, thereby securing to the second end 513 of the body, and an unlocked state when the lid assembly 515 can be removed from the second end of the body. Further, in the locked state, the sipper 521 is locked in a retracted position (FIGS. 7, 9A-9C, 11B), and in the 60 unlocked state, the sipper urged into the extended position (FIGS. 9D-9F, 10A-10B, 11A).

The lid assembly 515 also includes an access control device 524 carried by the lid housing 516 and coupled to the mechanical assembly 523. The access control device 524 is 65 configured to cause the mechanical assembly 523 to switch between the locked state and the unlocked state based upon a security token (e.g., typed button code or wirelessly

received token). For example, in the illustrated embodiment, the access control device 524 illustratively includes a plurality of external buttons 529a-529c configured to receive a numeric security token.

In particular, the mechanical assembly 523 illustratively includes a motorized device 525, a linkage 526 coupled between the sipper 521 and the motorized device 525, and a bias device 527 (e.g., coil spring) coupled to the linkage and configured to bias the mechanical assembly to be in the locked state. The latch 522 illustratively comprises a pinlock body 530 coupled to the linkage 526, and a pin 531 coupled to the pinlock body and configured to extend into the adjacent portions of the body 511 in the locked state and retract from the adjacent portions of the body in the unlocked state. In the illustrated embodiment, the pin 531 and the latch 522 are coupled together.

The sipper 521 illustratively includes a sipper housing 532 defining a fluid passageway 533 therethrough, and first and second arms 534a-534b extending from the sipper housing and to be received by the linkage 526. The linkage 526 comprises first and second linkage arms 535a-535b configured to respectively receive the first and second arms 534a-534b of the sipper 521, and a medial arm 536 between and extending opposite to the first and second linkage arms and to cooperate with the motorized device 525. Each of the first and second linkage arms 535a-535b comprises a transverse pin 538a (only one shown) cooperating with the pinlock body 530.

Also, the motorized device 525 illustratively comprises an electric motor 537 coupled to the access control device 524, and a cam 540 coupled to the electric motor and to abut and push the linkage 526 into the unlocked state. The motorized device 525 comprises a waterproof diaphragm 541 covering the cam 540. The waterproof diaphragm 541 is useful for maintaining a waterproof barrier between electronics in the access control device 524 and the motorized device 525, and the cavity 514. In some embodiments (FIG. 13), the access control device 524 may comprise a wireless access control device configured to receive the security token wirelessly from a wireless communications device.

Referring now to FIGS. 9A-9F, the toggling between the locked state (FIG. 9A) and the unlocked state (FIG. 9E) is described in detail. In FIG. 9A, the locked state comprises the latch 522 engaged with a distal and recessed portion 546 a peripheral slot 542 in the body 511. As perhaps best seen in FIG. 8, the user would insert the lid assembly into the body and twist it to lock it into opposing peripheral slots 542 in the body 511. The latch 522 is pushed into the peripheral slot 542 via the pin 531 of the pinlock body 530. The pinlock body 530 is pushed outward by the transverse pins 538a of the first and second linkage arms 535a-535b. This locked state is locked in via the bias device 527, which compresses the linkage 526 against a ledge 543 of the upper housing 520. In some embodiments, the bias device 527 may be positioned diagonally (noted with dashed box in FIG. 9A) to provide partial upward force on the linkage 526 to prevent dislodgment of the linkage due to external forces (e.g., by forcefully knocking the secure beverage container 510 on tabletop). Further, the sipper 521 is locked in a retracted position, and access to the fluid passageway 533 is fully sealed via a sipper door 544.

When the access control device 524 receives a secure token, the mechanical assembly 523 is caused to exit the locked state, which begins in FIG. 9B. The electric motor 537 causes the cam 540 to rotate, which causes the waterproof diaphragm 541 to move downward toward the medial arm 536 of the linkage 526. In FIGS. 9C-9E, as the water-

proof diaphragm 541 moves the medial arm 536 downward, the linkage is slid downward off the ledge 543, which releases the bias device 527, pushes the linkage and pinlock body 530 away from the latch 522, and rotates the sipper 521 upward. When the user desires to place the mechanical assembly 523 into the locked state, the user presses downward on the sipper 521, which cocks the linkage 526 between the bias device 527 and the ledge 543.

Another aspect is directed to a method for making a 10 secure beverage container 510. The method includes forming a body 511 comprising a first end 512, a second end 513 opposing the first end, a first longitudinal side extending between the first end and the second end, and a second longitudinal side opposing the first longitudinal side and extending between the first end and the second end. The first end 512 is closed, and the second end 513 is open. The body 511 defines a cavity 514 therein to receive a beverage fluid. The method also includes positioning a lid assembly 515 to be received by the second end 513 to seal the cavity 514 in 15 the body 511 and comprising a lid housing 516, a sipper 521 carried by the lid housing and providing access to the cavity 514, a latch 522 carried by the lid housing and configured to selectively latch to adjacent portions of the body, and a mechanical assembly 523 carried by the lid housing and 20 coupled to the sipper and the latch. The mechanical assembly 523 is configured to operate in one of a locked state where the latch 522 is latched to the adjacent portions of the body 511, thereby securing to the second end 513 of the body, and an unlocked state when the lid assembly 515 can 25 be removed from the second end of the body. The lid assembly 515 also includes an access control device 524 carried by the lid housing 516 and coupled to the mechanical assembly 523, the access control device configured to cause the mechanical assembly to switch between the locked state 30 and the unlocked state based upon a security token.

Referring now additionally to FIG. 13 and a flowchart 1000 therein, the flowchart shows logical operations for a companion software application that operates on a mobile wireless communications device.

40 It should be appreciated that features from any of the above embodiments of the secure beverage container 10, 110, 210, 310, 410, 510 may be combined with each other.

Many modifications and other embodiments of the present disclosure will come to the mind of one skilled in the art 45 having the benefit of the teachings presented in the foregoing descriptions and the associated drawings. Therefore, it is understood that the present disclosure is not to be limited to the specific embodiments disclosed, and that modifications and embodiments are intended to be included within the scope of the appended claims.

The invention claimed is:

1. A secure beverage container comprising:
a body comprising a first end, a second end opposing the first end, a first longitudinal side extending between the first end and the second end, and a second longitudinal side opposing the first longitudinal side and extending between the first end and the second end, the first end being closed, the second end being open, the body defining a cavity therein to receive a beverage fluid; and
a lid assembly to be received by the second end to seal the cavity in the body and comprising
a lid housing,
a sipper carried by the lid housing and providing access to the cavity,
a latch carried by the lid housing and configured to selectively latch to adjacent portions of the body,

11

a mechanical assembly carried by the lid housing and coupled to the sipper and the latch, the mechanical assembly configured to operate in one of a locked state where the latch is latched to the adjacent portions of the body, thereby securing to the second end of the body, and an unlocked state when the lid assembly can be removed from the second end of the body, and an access control device carried by the lid housing and coupled to the mechanical assembly, the access control device configured to cause the mechanical assembly to switch between the locked state and the unlocked state based upon a security token.

2. The secure beverage container of claim 1 wherein the mechanical assembly comprises a motorized device, a linkage coupled between the sipper and the motorized device, and a bias device coupled to the linkage and configured to bias the mechanical assembly to be in the locked state.

3. The secure beverage container of claim 2 wherein the latch comprises a pinlock body coupled to the linkage, and a pin coupled to the pinlock body and configured to extend into the adjacent portions of the body in the locked state and retract from the adjacent portions of the body in the unlocked state.

4. The secure beverage container of claim 3 wherein the sipper comprises a sipper housing defining a fluid passage-way therethrough, and first and second arms extending from the sipper housing and to be received by the linkage.

5. The secure beverage container of claim 4 wherein the linkage comprises first and second linkage arms configured to receive the first and second arms of the sipper, and a medial arm between and extending opposite to the first and second linkage arms and to cooperate with the motorized device.

6. The secure beverage container of claim 5 wherein each of the first and second linkage arms comprises a transverse pin cooperating with the pinlock body.

7. The secure beverage container of claim 2 wherein the motorized device comprises an electric motor coupled to the access control device, and a cam coupled to the electric motor and to abut and push the linkage into the unlocked state.

8. The secure beverage container of claim 7 wherein the motorized device comprises a waterproof diaphragm covering the cam.

9. The secure beverage container of claim 1 wherein the access control device comprises a wireless access control device configured to receive the security token wirelessly from a wireless communications device.

10. A secure beverage container comprising:
a body comprising a first end, a second end opposing the first end, a first longitudinal side extending between the first end and the second end, and a second longitudinal side opposing the first longitudinal side and extending between the first end and the second end, the first end being closed, the second end being open, the body defining a cavity therein to receive a beverage fluid; and
a lid assembly to be received by the second end to seal the cavity in the body and comprising
a lid housing,
a sipper carried by the lid housing and providing access to the cavity,
a latch carried by the lid housing and configured to selectively latch to adjacent portions of the body,

12

a mechanical assembly carried by the lid housing and coupled to the sipper and the latch, the mechanical assembly configured to operate in one of a locked state where the latch is latched to the adjacent portions of the body, thereby securing to the second end of the body, and an unlocked state when the lid assembly can be removed from the second end of the body, the mechanical assembly comprising
a motorized device,
a linkage coupled between the sipper and the motorized device, and
a bias device coupled to the linkage and configured to bias the mechanical assembly to be in the locked state, and
a wireless access control device carried by the lid housing and coupled to the mechanical assembly, the wireless access control device configured to receive a security token wirelessly from a wireless communications device, and
cause the mechanical assembly to switch between the locked state and the unlocked state based upon the security token.

11. The secure beverage container of claim 10 wherein the latch comprises a pinlock body coupled to the linkage, and a pin coupled to the pinlock body and configured to extend into the adjacent portions of the body in the locked state and retract from the adjacent portions of the body in the unlocked state.

12. The secure beverage container of claim 11 wherein the sipper comprises a sipper housing defining a fluid passage-way therethrough, and first and second arms extending from the sipper housing and to be received by the linkage.

13. The secure beverage container of claim 12 wherein the linkage comprises first and second linkage arms configured to receive the first and second arms of the sipper, and a medial arm between and extending opposite to the first and second linkage arms and to cooperate with the motorized device.

14. The secure beverage container of claim 13 wherein each of the first and second linkage arms comprises a transverse pin cooperating with the pinlock body.

15. The secure beverage container of claim 10 wherein the motorized device comprises an electric motor coupled to the wireless access control device, and a cam coupled to the electric motor and to abut and push the linkage into the unlocked state.

16. The secure beverage container of claim 15 wherein the motorized device comprises a waterproof diaphragm covering the cam.

17. A method for making a secure beverage container, the method comprising:
forming a body comprising a first end, a second end opposing the first end, a first longitudinal side extending between the first end and the second end, and a second longitudinal side opposing the first longitudinal side and extending between the first end and the second end, the first end being closed, the second end being open, the body defining a cavity therein to receive a beverage fluid; and
positioning a lid assembly to be received by the second end to seal the cavity in the body and comprising
a lid housing,
a sipper carried by the lid housing and providing access to the cavity,
a latch carried by the lid housing and configured to selectively latch to adjacent portions of the body,

13

- a mechanical assembly carried by the lid housing and coupled to the sipper and the latch, the mechanical assembly configured to operate in one of a locked state where the latch is latched to the adjacent portions of the body, thereby securing to the second end of the body, and an unlocked state when the lid assembly can be removed from the second end of the body, and an access control device carried by the lid housing and coupled to the mechanical assembly, the access control device configured to cause the mechanical assembly to switch between the locked state and the unlocked state based upon a security token.
18. The method of claim 17 wherein the mechanical assembly comprises a motorized device, a linkage coupled between the sipper and the motorized device, and a bias device coupled to the linkage and configured to bias the mechanical assembly to be in the locked state.

14

19. The method of claim 18 wherein the latch comprises a pinlock body coupled to the linkage, and a pin coupled to the pinlock body and configured to extend into the adjacent portions of the body in the locked state and retract from the adjacent portions of the body in the unlocked state.
20. The method of claim 19 wherein the sipper comprises a sipper housing defining a fluid passageway therethrough, and first and second arms extending from the sipper housing and to be received by the linkage; wherein the linkage comprises first and second linkage arms configured to receive the first and second arms of the sipper, and a medial arm between and extending opposite to the first and second linkage arms and to cooperate with the motorized device; and
- 15 wherein each of the first and second linkage arms comprises a transverse pin cooperating with the pinlock body.
